ILLUMINABLE DISPLAY SIGN OR SIMILAR ARTICLE

Conrad J. Escalante, Los Alamitos, Calif. (½ Superior Outdoor Display Inc., 125 W. Gaylord St., Long Beach 13, Calif.)

Filed Aug. 24, 1964, Ser. No. 81,429

Term of patent 14 years

(Cl. D1—12)

FIGURE 1 is a front elevational view of an illuminable display sign or similar article embodying my new design; FIG. 2 is a side elevational view thereof; and

FIGS. 3 and 4 are top and bottom plan views thereof, respectively.

The broken-line representation of advertising matter, supporting structures and brackets is for purposes of illustration only.

I claim:

The ornamental design for an illuminable display sign or similar article, substantially as shown and described.
